LAP FORMING PICKER OR THE LIKE
Rodeheaver H. Rogers, Startex, S.C., assignor to Quality
Textile Industries, Inc., Spartanburg, S.C., a corpora-
tion of South Carolina
Filed Jan. 25, 1962, Ser. No. 168,650
20 Claims. (Cl. 242—55.1)

My invention relates to improvements in textile machinery and particularly to so-called "pickers," or other machines, in which a somewhat compressed fibrous lap of say cotton or the like, is further compressed and wound into a compressed cylindrical package.

In the case of prior art machines for this purpose, as they existed prior to that disclosed in the William F. Lee et al. application Serial Number 67,374, filed Nov. 4, 1960 now Patent No. 3,106,356 much time is lost in (1) removing a completed lap package therefrom; (2) depositing a lap arbor or pin in position for the formation of a succeeding package thereon; and (3) in restarting the machine. The machine of said Lee et al. application materially improved the lost time situations as to (1) and (2) supra, by the provision of improved machine frame-provided cheek plates at opposite ends of the lap package that is being formed. These Lee et al. cheek plates, by providing forward top edges inclined downwardly and rearwardly to their arbor-receiving seats, facilitate removal movement of a completed lap package over the adjacent forward end of the machine frame; and enable an arbor for a succeeding package to readily roll rearwardly into the cheek seats for the start of the next package.

It is therefore the primary object of the present invention to further improve the machine of the Lee et al. application, and for that matter, other lap winding machines, by providing means which may be readily incorporated therein for automatically restarting the machine for the formation of a succeeding lap package as soon as the arbor therefore is in its initial package building location, whether or not cheek plate-provided seats as such are provided.

Invention also resides in certain novel features of construction, combination and arrangement of the various parts, including means associated with the machine drive control lever and elements of its knockoff means for actuating said lever to its operative drive position.

Various other objects and advantages of the invention will be readily apparent to those versed in the art upon reference to the drawings in connection with the related descriptive matter.

In pursuance of statute requirements a now preferred example of the invention is dealt with herein. However, same should be considered as merely illustrative rather than limitative, since it will be obvious to knowledgeable persons in the textile field that my inventive concept is susceptible of various changes and modifications within the spirit and scope of the subject matter claimed herein-after.

In the drawings, wherein the same reference characters have been used to designate the same parts wherever they appear in the several views—

FIG. 1 is a frontal perspective view of a portion of the lap package-forming end of a cotton picker or the like and illustrating the application of my invention thereto;

FIG. 2 is a side perspective of the picker machine end shown in FIG. 1;

FIG. 3 is a fragmentary side elevational view of the opposite side of the machine with cheek plates 33 of FIGS. 1 and 2 and other parts deleted;

FIG. 4 is a section on the line 4—4 of FIG. 1, with the cheek plates 33 and other parts deleted as in FIG. 3;

2

FIG. 5 is a perspective detail of the ratchet wheel and the lifting means for the pawl of FIGS. 7 and 9;

FIG. 6 is a group perspective view of certain elements shown in FIGS. 1 and 5;

5 FIG. 7 is a perspective of the pawl and its crank shaft;

FIG. 8 is a perspective detail of the lever lifting cam means of FIGS. 1 and 2; and

FIG. 9 is a sectional detail view of the lifting means for the pawl of FIGS. 1 and 7.

Referring to the drawings, my invention is shown applied to the lap winding end of a familiar type cotton picker which includes a frame 10 on which are rotatably mounted the usual pair of fluted lap package forming and supporting rollers 12 and 14 in closely adjacent parallel positions. The rollers 12 and 14 are provided with gears 13 and 15, respectively, by which they are positively driven by any suitable driving means (not shown) through a pulley 20 mounted on shaft 21 which latter drive gears 13 and 15 through gears 22, 24 and 26 as indicated in FIG. 3.

10 In the art machine referred to, lap 16 of textile fibers supplied by conventional opening and picking mechanism, not shown, passes over the rear roller 14 and is compressed and wound up into a compressed cylindrical package 17 on a lap arbor or pin 18 overlying said rollers 12 and 14, and frictionally rotated thereby.

15 In the operation of the machine, end portions of the lap arbor or pin 18 rotatably engage in inverted U-form bearings 28 of heads 29 for movement in a vertical plane substantially perpendicular to the plane of the axes of rollers 12 and 14 and midway between said axes. Each bearing-providing head 29 is mounted on the upper end of a rack 30 which is slidable up and down in a substantially vertical track 32 on frame 10 (see FIGS. 3 and 4).

20 In order to maintain the arbor receiving head bearings 28 at equal distances from the axes of rollers 12 and 14 as the lap arbor 18 rises due to the increasing size of the lap package 17, a positive mechanical connection is provided between the arbor bearings 28, comprising pinions 34 mounted on a common shaft 36 engaging racks 30. Thus any vertical movement of one bearing providing head 29 will be transmitted to the other head 29, ensuring equal movement of said bearing providing heads and at all times maintaining the axis of arbor 18 parallel with the axes of rollers 12 and 14. By reason of this, the lap package 17 will be compressed to a constant thickness widthwise of said lap and ensure the formation of the necessary cylindrical package 17.

25 As the lap package builds, and the end portions of the lap arbor or pin 18 rise from the seats 31 which are provided by the usual cheek plates 33, they are sustained against rearward movement by the upstanding cheek plate provided shoulders 35 which are extensions of the rear walls of seats 31.

30 It should be noted here that the cheek plates 33 are dealt with in the aforementioned co-pending application of William F. Lee et al., and that they provide the downwardly inclined forward top edges 33a which communicate with the seats 31. Thus, as shown, a pin 18a for a

35 succeeding package 17 which is supported on said edges 33a will make a beneficial compressing, or ironing, engagement with the package 17 being built. Then after the package 17 is removed, the second pin or arbor 18a simply rolls into cheek seats 31 for the start of a succeeding lap package 17. The cheek plates 33 have J-form forward terminals 37 for the support of a reserve pin or arbor 18, not shown.

40 Referring back to the art machine as herein illustrated, the pressure between the lap arbor or pin 18 and the rollers 12 and 14 is provided by a reversible compressed air motor generally designated at 40. This motor 40 is mounted at the bottom of frame 10 and the outer portion

of its piston shaft 44 is constituted as a rack 44a engaging a pinion 45 on shaft 36.

The fluid motor 40 has a casing 42 and a piston 44b which forms in said casing a rear chamber 46 and a forward chamber 48. Lines 50 and 52 are provided to connect said chambers 46, 48 to a conventional four-way valve 54 which is supplied with air (or for that matter, fluid) at suitable pressure by line 62, a reducing valve 60 and a line 58 between said reducing valve and said four-way valve. Operation of the four-way valve 54 is controlled by the upwardly biased foot treadle 56 to normally connect line 52 and the forward chamber 48 of fluid pressure motor 40 to the fluid under pressure in line 58 to normally maintain the arbor bearing-providing heads 29 in their lowermost position.

In the art machine the treadle 56 of the four-way valve 54 is arranged to be automatically operated by a knockoff mechanism which differs in certain details from that shown, to raise the bearing-providing rack heads 29 when the lap package 17 has reached a desired size so that the lap package may be removed from the machine.

However, I have made improvements in the usual treadle 56 operating means, as will be hereinafter explained.

The knockoff mechanism, to be presently described, is further arranged to interrupt the drive connection to the fluted lap package supporting rollers 12, 14 and to the usual calender rolls (not shown) which compress the lap 16 prior to its delivery to rollers 12 and 14 and lap arbor 18. The knockoff arrangement is such as to break 30 the lap 16 and effect the winding of the broken end on lap package 17.

The Drive Interrupting Means of the Prior Art (see FIGS. 1 and 2)

Referring to FIGS. 1 and 2, the end of the power supply shaft 21, on which pulley 20 is mounted, is pivotally mounted on the frame 10 in the usual self-aligning bearing, not shown. The opposite end of said power supply shaft 21 is rotatably mounted on a lever 72, said lever 72 being pivoted on a stud 73 on frame 10 (see FIG. 2). A gear 74 mounted on shaft 21 adjacent said lever 72 is provided to engage a gear 76 for driving the usual calender rolls (not shown), said gear 76 having its shaft rotatably mounted in the usual frame-provided bearing (not shown).

The gear 78 concentric with and driven by gear 76 drives a gear 80, said gear 80 being mounted for swinging movement by means of an upstanding L-form post 82 which is pivoted intermediate its ends as at 83 to an exterior side of frame 10 (see FIGS. 2 and 4). Gears 50 78 and 80 are provided with co-acting hunting-teeth 84 and 86 so that when hunting-tooth 84 on gear 78 contacts tooth 86 on gear 80, said gear 80 and its carrier post 82 will be swung counterclockwise about pivot 83 (FIG. 2) away from gear 78 and against the action of coil spring 81. Spring 81 has one end connected (81a) to post 82 and the other end to frame-carried pin 81b. Upon counterclockwise rocking of post 82 (FIG. 2) the usual connections 88, 88a, 88b between the foot end of post 82 and the vertically pivoted finger 90 actuates the latter outwardly to release the conventional knockoff lever 91.

The knockoff lever 91 is pivoted as at 92 to frame bracket 93 and has the shoulder 91b which supports the gear-carrying lever 72 in its upper or machine drive position. Thus, when kickoff lever 91 is actuated outwardly, lever 72 drops in the bracket provided guide slot 93a to disconnect gears 74, 76 and the machine stops. A pull-down spring 72x is connected to levers 72 and to frame 10 (see FIG. 2).

In the art machine, and here, the knockoff lever 91 has the inwardly extended lower end and the weight 91a thereon tending to actuate it inwardly to support lever 72.

There is also here provided the usual pivoted link connection 94 between lever 72 and the inner end of foot 75

pedal 95 which is fast on shaft 96 which is journalled in the floor or base supported bearing unit 95b. Foot pedal shaft 96 terminates in the usual crank 96a, but instead of depressing the air valve control pedal 56, as in the prior art, to directly effect elevation of the bearing provided heads 29, said crank 96a participates in the control of the bearing heads 29 in a different way which will now be explained.

The Novel Pawl and Ratchet Assembly Relation to Air Control Pedal 56 (FIGS. 1 and 5)

As shown in FIG. 1, and in greater detail in FIG. 7, the crank 96a has the collar 96x inwardly of its free end and also crank 96a has loose thereon the pawl 97 which is located just outwardly of collar 96x. The tooth end of pawl 97 plays over the teeth of a ratchet wheel 98 which is fast on a shaft 99 which has a crank end 99a overlying the air valve control pedal 56 of FIG. 1. This ratchet wheel shaft 99 is journalled in the bearings 100 of a floor-supported unit 102. A spring 104 (FIG. 7) is anchored to pawl 97 and to an adjacent collar 106, fast on the outer end of crank 96a so as to normally urge the tooth end of pawl 97 to engage the teeth of ratchet wheel 98. The pawl 97 also has the lateral stud 97a adjacent its tooth end.

Automatic Stopping of the Machine and Raising of Arbor Bearing Heads 29 Upon Package 17 Completion (FIGS. 1, 2 and 5)

As shown, the machine is in operation but the hunting teeth—of gears 78, 80—will shortly rock the post (82) carried gear 80 about post pivot 83 (FIG. 2) and away from gear 78. Such movement of the gear carrying post 82 acts through finger 90 to actuate knockoff lever 91 outwardly and allow the drive gear-carrying lever 72 to drop to disengage gears 74 and 76. Downward movement of lever 72 is accelerated by pull-down spring 72x (FIG. 2). Such movement of lever 72, in addition to stopping the machine, effects depression of the air valve controlling pedal 56 of FIG. 1 to raise bearing heads 29. There is a novel means including crank 99a (FIGS. 1 and 5) for the position control of the upwardly biased pedal 56 and same will be presently described.

When the machine is operating with the air valve control pedal 56 "up" the crank end 99a of the ratchet wheel shaft simply rests on pedal 56 and exerts no down pressure thereon, as will be hereinafter explained.

However, when the knockoff lever 91 is actuated outwardly manually or by finger 90 (FIG. 2) to effect disengagement of gear 74 from gear 76 to stop the machine, the dropping of lever 72 acts through link 94, pedal 95 and its crank shaft 96, 96a to actuate the crank 96a and pawl 97 rearwardly and downwardly. Thus, pawl 97 functions to turn ratchet wheel 98 to cause its crank 99a to depress the valve control pedal 56 to elevate bearing heads 29.

With the bearing heads 29 elevated the lap package 17 can be rolled forwardly over the next-to-be-used arbor, or pin 18a and over the forward end of the machine. This permits pin 18a (FIG. 1) to roll down the inclined top cheek edges 33a and into the cheek-provided seats 31 to restart the machine and to commence the building of the next lap package on said pin or arbor 18a through means which will now be described.

The Arbor 18 Operated Means for Restarting the Machine (FIGS. 1, 2, 5 and 6)

Referring to FIGS. 1 and 2, when the replacement arbor 18a rolls into cheek seats 31 it depresses the normally raised rear end of rock lever 108 which latter is pivoted as at 110, intermediate its ends, to the side of the frame 10. This raises the forward end of said lever 108 which is pivoted as at 112 to the upper end of the depending link 114 whose lower end is pivoted at 116 to the forward end of a rearwardly extending lever 117. As

shown in FIG. 2, the rear end of lever 117 is pivoted at 118 to the inner side portion of the frame 10.

Intermediate its end the lever 117 provides the slot 119 for the pivot stud 120 (FIGS. 1 and 6) which is carried by the upstanding vertically slideable post 122 working in the guideway 125 of the guide member 124 of FIGS. 1 and 5. This guide member 124 is secured to the ratchet wheel carrying unit 102 by side cleats 126 extending rearwardly from the latter. These cleats 126 are slotted to receive bolts 128 whereby the guide member 124 can be adjusted toward and from the ratchet wheel 98. The forward wall of the guide member 124 has the slot 130 through which projects the post-carried latch-form lug 132 which latter, when the arbor operated lever 108 is in the FIG. 2 position, will be disposed under the stud 97a of the pawl 97, as will be presently explained.

As shown in FIGS. 5 and 6, a backing plate 134 in guideway 125 and backed by a spring 136 which is secured by stud 138 normally maintains lug 132 projected through guide slot 130.

Bearing Heads 29 Lowered Before Machine Started

It is important that the bearing providing heads 29 be lowered approximately to the FIGS. 1 and 2 position before the machine is started. Therefore, this head lowering is effected first. Thus, when the replacement arbor 18a depresses the end of lever 108 to raise link 114 and lever 117 along with post 122, the latch lug 132 engages the pawl stud 97a (FIGS. 7 and 9) and lifts the pawl 97 to disengage it from the teeth of the ratchet wheel 98.

The above referred to lifting of pawl 97 admits of upward movement of the crank end 99a of the ratchet wheel shaft 99 under the influence of the upwardly biased valve control pedal 56. Upward movement of pedal 56 acts through valve 54, as heretofore mentioned, to lower the bearing-providing heads 29 to arbor-engaging position of FIGS. 1 and 2 through the action of the piston rack 44a, shaft 96, rack bars 30, etc. As post 122 continues upwardly the pawl stud 97a disengages from post lug 132 and pawl 97 drops back into engagement with the teeth of ratchet wheel 98.

While shaft 36 is rotating to lower the bearing providing heads 29 through the action of pinions 45 and rack bars 30 (FIG. 4), novel cam means on the shaft 36 is approaching a position with respect to lever 72 which will effect raising of said lever 72 to start the machine and permit the knockoff lever 91 to resume its lever 72 supporting position of FIGS. 1 and 2.

The Cam Means 165 for Resetting Starting Lever 72 (FIGS. 2 and 5)

In carrying out the invention, the piston-operated control shaft 36 for the heads 29 is elongated, as shown in FIGS. 2 and 8, to provide the end 36a, on which is keyed a pinion 140. This pinion 140 meshes with gear 142 which is fast on stub shaft 144 which is journaled in upstanding bearings 146 and 148. These bearings 146 and 148 are suitably secured to the bight portion 148 of a generally inverted U-form bracket having depending legs 152 and 154. Leg 152 of said U-form bracket 150 is bolted as at 156 to the side of the machine frame 10 and the longer leg 154 is bolted at 158 to the upstanding support 160 having the base 162 which is secured as at 164 to the floor or other supporting surface.

Secured adjacent the inner end of the stub shaft 144 is the cam 165 which is disposed in plane with the lever 72 and below the latter. The ratio of gears 140 and 142 is such that by the time shaft 36 has lowered the bearing providing head members 29 to the FIG. 1 position, the cam 165 will have elevated lever 72 to its FIG. 2 position to re-start the machine through engagement of the lever-carried gear 74 with gear 76. At the same time knockoff lever 91 assumes its inward FIG. 2 position wherein its notch 91b (FIG. 1) supports lever 72 to retain gear 74 in engagement with gear 78. It will be understood that

spring 81 (FIG. 2) rocks post 82 to re-engage gears 80, 78 as soon as hunting teeth 84, 86 disengage.

The Depressing of the Valve Pedal 56 by Means directly Connected to Knockoff Lever 91 for Emergency Stopping of the Machine (FIGS. 1 and 2)

For emergency stopping of the machine, the weighted end 91a of the knockoff lever 91 has the pivot connection 166a with the adjacent end of a rock lever 166 which is pivoted 168 to a bearing bracket 169 which latter is secured to the inner surface of one end wall of the frame 10 as shown in FIG. 1. The outer end of the rock lever 166 has the downturned portion 170 providing the foot 170 which, when the knockoff lever is in its operative lever 72 supporting position shown in FIG. 1, will be elevated above the valve control pedal 56.

In the normal operation of the machine, which is to say, the stopping of same by engagement of the hunting-teeth 84, 86 of gears 78 and 80, the knockoff lever 91 is not moved outwardly far enough for the foot portion 170 of rock lever 166 to engage and depress the valve control pedal 56 to elevate the bearing providing heads 29. However, when the machine is to be stopped as in the case of an emergency, the knockoff lever 91 will be pulled outwardly to its outward limit against the action of weight 91a and a spring 172; and this causes sufficient rocking of lever 166 to cause its foot 170 to engage and depress pedal 56 to elevate heads 29. As air valve pedal 56 is thus depressed, the crank end 99a of the shaft 99 of ratchet wheel 98 drops down with said pedal 56, and the engagement of pawl 97 with the ratchet wheel teeth will hold the crank end 99a of shaft 99 in lever-depressing position. When the operator releases the knockoff lever 91, its weight 91a and the spring 172 actuate it against the side of the now lowered lever 72 so as to be ready to move inwardly to support the latter when it is raised by cam 165. The foot 170 of lever 166 is, of course, lifted away from air valve pedal 56 by the action of weight 91a and spring 172 immediately the operator releases knockoff lever 91.

It will be understood that as the lap package 17 builds and arbor 18 rises, the forward end of the arbor-operated lever 108 gradually drops so that the weight of link 114 and lever 117 actuates post 122 downwardly in its bearing 124 by reason of the pin and slot connection 119, 120 between said post and lever 117. When the upwardly slanted bottom of post lug 132 engages the pawl stud 97a, the post 122 and its spring backed backing plate 134 is simply rocked rearwardly in guideway 125, which latter is oversized in a depthwise direction as shown. This permits post lug 132 to resume its starting position below pawl stud 97a so as to be ready to lift the pawl 97 the instant a replacement arbor 18a drops into the cheek provided seats 31.

From the foregoing it will be evident that my invention is readily applicable at but moderate cost to known types of lap forming machines to make them automatic in operation and without substantial modification of same.

Having thus described my invention, what I claim is:

1. In a lap package-forming textile machine having a frame, a shiftable machine drive control member carried by said frame, a driven removable arbor on which a package is formed and having an initial machine-provided starting position; the combination of arbor-actuated means shiftably carried by said frame and operated by said arbor when the latter is located in its package starting position, actuating means for said drive control member for moving the latter to machine drive position, and an operative connection between said arbor-actuated means and the control member actuating means for starting the machine upon operation of the arbor-actuated means.
2. The combination set forth in claim 1, and vertically shiftable bearing-providing heads carried by said frame and movable from an elevated inoperative position to a

75

lowered position in which they engage end portions of the arbor, and an operative connection between said bearing-providing heads and said arbor-actuated means for lowering said heads to arbor-engaging position upon operation of said arbor-actuated means.

3. The combination set forth in claim 2, and said operative connection between said bearing-providing heads and the arbor-actuated means including a portion of the actuating means for said drive control member.

4. The combination set forth in claim 2, and a common rotatably driven shaft incorporated in the actuating means for each of said drive control member and said bearing-providing heads.

5. The combination set forth in claim 4, and the operative connection between said bearing-providing heads and arbor-actuated means including depending rack bars supporting said bearing-providing heads and guided in said frame, pinions on said shaft and operating said rack bars, said drive control member being movable upwardly to operative position, a subjacent drive control member-operating cam operatively connected to said shaft for lifting said drive control member to machine drive position, and knockoff means carried by said frame and operative to engage and support said drive control member in machine drive position after it has been moved there-to by said cam.

6. The combination set forth in claim 1, and parallel upper frame portions at opposite sides of the machine adjacent the package building end thereof, said frame portions having aligned arbor-receiving seats defining the starting position for an arbor in the building of a package, and said frame portions having upper edges inclined downwardly to said seats from adjacent said machine end whereby a second arbor for a succeeding package can be disposed on said upper frame edges during the building of a package so that when the latter is removed from the machine the second arbor will simply roll into said seats to restart the machine for the building of the next package.

7. The combination set forth in claim 2, and parallel upper frame portions at opposite sides of the machine adjacent the package building end thereof, said frame portions having aligned arbor-receiving seats defining the starting position for an arbor in the building of a package, and said frame portions having upper edges inclined downwardly to said seats from adjacent said machine end whereby a second arbor for a succeeding package can be disposed on said upper frame edges during the building of a package so that when the latter is removed from the machine the second arbor will simply roll into said seats to restart the machine for the building of the next package.

8. The combination set forth in claim 3, and parallel upper frame portions at opposite sides of the machine adjacent the package building end thereof, said frame portions having aligned arbor-receiving seats defining the starting position for an arbor in the building of a package, and said frame portions having upper edges inclined downwardly to said seats from adjacent said machine end whereby a second arbor for a succeeding package can be disposed on said upper frame edges during the building of a package so that when the latter is removed from the machine the second arbor will simply roll into said seats to restart the machine for the building of the next package.

9. The combination set forth in claim 4, and parallel upper frame portions at opposite sides of the machine adjacent the package building end thereof, said frame portions having aligned arbor-receiving seats defining the starting position for an arbor in the building of a package, and said frame portions having upper edges inclined downwardly to said seats from adjacent said machine end whereby a second arbor for a succeeding package can be disposed on said upper frame edges during the building of a package so that when the latter is removed from the machine the second arbor will simply

roll into said seats to restart the machine for the building of the next package.

10. The combination set forth in claim 5, and parallel upper frame portions at opposite sides of the machine adjacent the package building end thereof, said frame portions having aligned arbor-receiving seats defining the starting position for an arbor in the building of a package, and said frame portions having upper edges inclined downwardly to said seats from adjacent said machine end whereby a second arbor for a succeeding package can be disposed on said upper frame edges during the building of a package so that when the latter is removed from the machine the second arbor will simply roll into said seats to restart the machine for the building of the next package.

11. In a lap package-forming textile machine having a frame, a shiftable machine drive control member biased to assume a machine drive-interrupting position and carried by said frame, a driven removable arbor on which a package is formed, vertically shiftable bearing-providing heads carried by said frame and movable from an elevated inoperative position to a lowered operative position in which they engage end portions of the arbor, actuating means operatively connected to said bearing-providing heads for moving the same to and from operative position, a control member for said head-actuating means, and a knockoff lever for supporting said drive control member in its machine drive position; the combination of a movable member operatively connected to said knockoff lever and actuated by shifting of the latter out of drive control member-supporting position to engage and operate said head-actuating-means to elevate said heads to their inoperative position.

12. The combination set forth in claim 11, and said movable knockoff lever-operated member comprising a rock lever pivoted intermediate its ends to the machine frame and at one end to said knockoff lever, the other end of said rock lever operable to engage and operate the control member of said head actuating means, and yielding means tending to maintain said rock lever in inoperative position and said knockoff lever in its operative position.

13. In a lap package forming machine, the combination of a machine drive control lever, a driven arbor on which a lap package is to be formed, bearing-providing head blocks movable to and from arbor-engaging position, actuating means for the head blocks, a control member for said head block-actuating means and biased to normally maintain the head blocks in operative arbor-engaging position, a first crank shaft having a crank portion, a bearing support for said first crank shaft, a machine drive control lever-operated rocking means for said first crank-shaft and connected thereto inwardly of its crank portion, for operation by shifting movement of said control lever, a ratchet gear, a second crank shaft on which said ratchet gear is fast, said second crank shaft having a crank portion adjacent one end, a bearing support for said second crank shaft, a pawl loose on the crank portion of said first shaft and spring-biased to normal operative engagement with said ratchet gear, the crank end portion of said second crank-shaft operatively aligned with said head block-actuating means control member to engage and move same to actuate the head blocks to inoperative elevated position when the drive control lever is moved out of machine drive position, means operable by the location of an arbor in package-starting position for lifting said pawl out of engagement with said ratchet gear to relieve said block-actuating means control member of the holding pressure of the second shaft crank, whereby to effect return the head blocks to operative position, a machine drive control lever actuating means operable to return the drive control lever to machine drive position, and an operative connection between said last named means and said arbor-actuated means for starting the machine following arbor actuation operation of the latter.

14. The structure of claim 13, and said machine drive control lever actuating means including a portion of said head block-actuating means.

15. The structure of claim 13, and said head block-actuating means including a rotatably driven shaft, and said machine drive control lever actuating means comprising a cam operatively connected to said shaft aligned with said starting lever.

16. In a lap package forming machine, including a removable arbor on which a package is to be formed, rotatable drive means for rotating said arbor, a drive control member for said arbor drive means, actuating means for said arbor drive control member, shiftable arbor engageable head blocks, actuating means for moving said head blocks to and from arbor engaging position, and an operative connection between said head block-actuating means and said arbor drive control member-actuating means, for operating the latter only after the head blocks have been actuated to approximately arbor-engaging position.

17. The structure of claim 16, and a rotatable shaft incorporated in said head block actuating means, and the actuating means for said drive control member comprising a cam operatively connected to and driven by said shaft.

18. In a lap package-forming machine, a drive control member, actuating means for said drive control member, arbor-engaging head blocks, actuating means for moving said head blocks to and from arbor-engaging position, an operative connection between said head block-actuating means and drive control member actuating means for effecting starting of the machine when the head blocks are actuated toward arbor-engaging position, said machine comprising a frame, arbor seats provided by said frame at opposite sides, arbor-actuated means adjacent one of said seats, and an operative connection between said arbor-actuated means and said head block-actuating

means for moving the head blocks to arbor-engaging position and starting the machine upon placement of an arbor in said seats.

19. In a lap package-forming machine, comprising a frame, parallel supporting and drive rolls for a lap arbor on which a lap package is to be wound, frame-carried drive means for said arbor drive rolls, a control member for said roll drive means, said control member carried by said frame adjacent the bight between said arbor drive rolls for operation by an arbor to actuate said roll drive means, and head blocks carried by said frame and mounted for movement to and from engagement with an arbor which is supported by said rolls, frame-carried actuating means for said head blocks, and an operative connection between said arbor-operated control member and the head block-actuating means for bringing the head blocks into arbor-engaging position when the roll drive means control member is actuated to roll-drive position by an arbor.

20. In a lap package-forming machine, comprising a frame, parallel drive rolls for a lap arbor on which a lap package is to be wound, said rolls providing an arbor-supporting bight, frame provided arbor receiving seats at opposite sides of the machine and aligned with said roll-provided bight, frame provided drive means for said arbor drive rolls, a control member for said drive means, and said control member carried by the frame adjacent one of said seats and the bight between said arbor drive rolls for operation by an arbor to actuate said roll drive means.
